UNITED STATES PATENT OFFICE.

JOHN F. TOOMEY, OF NEW YORK, N. Y., ASSIGNOR TO AMERICAN TELEPHONE AND TELEGRAPH COMPANY, A CORPORATION OF NEW YORK.

TELEPHONE CALL-WIRE CIRCUITS.

1,383,038.

Specification of Letters Patent. Patented June 28, 1921.

Application filed June 10, 1919. Serial No. 303,054.

To all whom it may concern:

Be it known that I, JOHN F. TOOMEY, residing at New York, in the county of New York and State of New York, have invented 5 certain Improvements in Telephone Call-Wire Circuits, of which the following is a specification.

This invention relates to telephone circuits, and more particularly to telephone 10 call wire circuits.

In practice upon the occasion of a subscriber wishing to converse with another subscriber and making known his desire to an operator at a central office, if the called 15 subscriber is found to be connected with that particular office, the call may be completed thereat. If, however, the line of the desired subscriber be connected to a distant office, it is necessary that a common conductor 20 shall be provided between the two offices with which the lines of both subscribers may be connected, and which thus furnishes a link of communication commonly known as a trunk line. It is also necessary to provide 25 means whereby an operator at a central office is enabled to communicate with another operator stationed at a distant office in order that the said second operator may assign to the central office operator which one of the 30 trunk lines it is desired shall be employed for the connection. For this purpose at each initiating operator's position there are provided a plurality of keys or buttons, each adapted when operated to complete a circuit 35 to a distant office. These are ordinarily termed call wire circuits. In previous call wire systems, the circuits were so arranged that either one or all the operators in the same office could bridge their telephone sets 40 across the call wire circuit at the same time. This feature caused considerable trouble, because the connection of a large number of operators' sets to the call wire circuit at the same time reduced the transmission efficiency 45 to a point where it was difficult to pass calls over the circuit. One of the cardinal features of this invention consists in the provision of means whereby a call wire circuit is adapted to be used by only one operator at 50 a time, the circuit being rendered inoperative at such time to a second operator and thereby providing higher transmission efficiency. Other and further features of the invention will hereinafter appear.

55 This invention may now be more fully

understood by reference to the accompanying drawing, in which one embodiment is diagrammatically illustrated.

In the arrangements of the invention there are shown two telephone switchboard positions 5 and 6, together with the essential elements pertaining to this improved circuit. While but two positions are illustrated, it will be understood that a plurality of positions may be provided at a central office, and 60 each position may be connected to an outgoing call wire circuit, comprising conductors 7 and 8 which terminate at a distant office. At each position there is provided 65 switching means in the form of a call wire 70 key or button, as indicated at 9 and 10. Associated with each call wire button is a position relay as represented by 11 and 12 at 75 positions 5 and 6. In series with, and common to said position relays is relay 13. This 80 relay is of sufficiently high resistance so that but one position relay can operate in series with it at one time. The resistance of the position relays is made as low as possible in order to provide a low resistance shunt to 85 ground to prevent the operation of a second position relay. Therefore, upon the depression of an initial call order button a circuit is provided by way of the position relay individual to said button and common relay 90 13 which operates both relays. The operation of the position relay causes it to attract 95 its armatures, thereby disconnecting the operator's set from the talking key and providing for the connection of said set with the order wire circuit. The operation of the relay 13 also connects battery through the back contacts of the other position relays to all of the busy signal lamps associated 100 with the call wire key at the different switchboard positions, except the one where the operator is using the circuit. The busy lamp at this position will not light, because its circuit is opened by the operation of the position relay thereat. The lighting of the 105 lamps will thus inform the operators at the other positions that the call wire circuit is being used. Should the operators ignore the busy signal and attempt to use the call wire circuit they will be unable to do so, because 110 their individual position relay cannot be operated on account of the low resistance ground that is connected with the common signaling relay 13 by the operation of the first call wire key. Furthermore, owing to

the high resistance of the common signaling relay 13, there would not be sufficient current to operate the second position relay.

The details of this circuit may be more 5 sufficiently understood from the following description of its operation.

The operator at position 5 upon desiring to communicate with a distant office will depress the call order wire key 9 which will 10 complete the following circuit: from ground, through said key 9, conductor 16, winding of relay 11, conductors 17 and 18, winding of relay 13 to grounded battery. This circuit will provide for the energization 15 of relays 11 and 13. The operation of relay 11 will cause it to attract its armatures, breaking the circuit with the talking key and providing for a circuit from the operator's telephone set by way of conductors 20 19 and 20 through the armatures of relay 11 and conductors 7 and 8 of the call wire circuit, and thence to the distant office. The operator at position 5 is thus enabled to communicate with the operator at the distant 25 station, who will make an assignment of a certain trunk, whereupon the initiating operator and distant operator will associate the plugs of the calling and called lines, respectively, with said trunk, thereby establishing a connection between the stations.

Upon the operation of common relay 13 its armature will be attracted and a circuit provided from ground, lamp 15, conductor 21, upper armature of relay 12 conductors 35 22 and 23, armature and contact of relay 13 to grounded battery. This circuit will provide for the lighting of the lamp 15 at position 6 and the operator thereat will be informed that the call order wire is being 40 used. If the operator at position 6 should ignore the busy signal 15, and should operate key 10 at the same time that key 9 was operated the relay 12 would not operate to connect the operator's set at position 6 to conductors 7 and 8. The relay 12 could not operate at the same time while relay 11 was 45 energized because a low resistance shunt to ground is provided by the operation of relay

11 over conductor 17, winding of relay 11, conductor 16, contact of key 9, to ground. 50 Furthermore, while there is sufficient current in the circuit closed upon the depression of key 9 to operate relay 11, the circuit closed by the simultaneous depression of key 10 will increase the resistance to such a degree as to 55 prevent the operation of relay 12. There will be, however, sufficient current in said circuit to maintain the relay 11 in its actuated condition. A like condition would prevail should any other operator at the associated 60 positions of the switchboard ignore the busy signal at her position.

While the arrangements of this invention have been illustrated as embodied in certain specific arrangements which have been 65 deemed desirable, it will be understood that they are capable of embodiment in many and widely varied forms without departing from the spirit of the invention as defined in the 70 appended claim.

Having thus described the invention, what is claimed is:

In a telephone system comprising a plurality of switchboard positions, a call order wire associated with said positions, switching means at each of said positions, signaling means at each position, a relay common to all of said positions and in series with said switching means, means controlled by the switching means at each position for completing a circuit for the relay at said position and said common relay, means controlled by said position relay for connecting said order wire to said position, means controlled by said position relay and said common relay 75 for preventing the simultaneous operation of any of the other of said relays, and means controlled by said position relay and common relay for operating the signaling means at only the positions which are not connected 80 with said call circuit.

In testimony whereof, I have signed my name to this specification this 7th day of June, 1919.

JOHN F. TOOMEY.
